UNITED STATES PATENT OFFICE

PETER A. ASPENLEITER, OF CINCINNATI, OHIO, ASSIGNOR, BY MESNE ASSIGNMENTS, TO UNITED AUTOGRAPHIC REGISTER CO., OF CHICAGO, ILLINOIS, A CORPORATION OF ILLINOIS

PAPER CUTTER

Application filed March 5, 1929. Serial No. 344,288.

This invention relates to an improved paper cutter which is designed with an object of preventing injury to the user of the cutter at the time of feeding paper between the 5 blades of the cutter.

A further object is to produce a paper cutter especially designed to be used in certain types of office appliances wherein continuous webs of paper are employed for purposes of 10 making records, and wherein portions of the webs are removable after having made such records.

A further object is to produce a paper cutter especially designed to be used where it 15 would be desirable to remove one or both of the knives of the cutter from proximity with the edges of the paper webs in order that they may be grasped and fed forwardly between the knives previous to the severing operation.

These and other objects are attained in the paper cutter described and claimed in the following specification and illustrated in the accompanying drawings, in which:

25 Fig. 1 is a fragmental side elevation, somewhat in section, showing an office appliance equipped with a paper cutter embodying my invention.

Fig. 2 is a view similar to Fig. 1, but showing the parts in different positions.

The machine in connection with which I have chosen to illustrate my invention is one especially designed to facilitate the typing of bill forms in multiple and is intended for 35 use with a typewriter construction, not shown, adapted to writing on flat platens. Such a machine consists essentially of a platen 3 which is flat and which is supported by longitudinal side bars or frame elements 4 resting upon legs 5.

In a typical form of the machine there is provided a clamping bar 6 which is adapted by suitable mechanism which will be described, to clamp the forward edges of a 45 series of webs 7 bearing the printed forms. These webs are aligned at their forward edges 8 over aligning pins or hooks 9 which enter perforations in the webs at their forward edges. Such a clamping bar 6 is mounted 50 on pins 10 on each side of the webs to be

clamped in a manner so that the pins reciprocate vertically and clamp or release the webs through the agency of the bar 6. The reciprocation is caused by the engagement of an operating pin 11 with the forked element 55 12 at the lower end of each pin 10, the pin 11 engaging the slot in the fork and being caused to move therein by means of the rocker arm 13 which carries each of the pins 11. This rocker arm is mounted on a shaft 60 14 extending between the sides 4 so that when the shaft 14 is rotated the rocker arm will move up or down to cause operation of the clamping bar 6. Each rocker arm has a forked end 15 in which a pin 16 on a lever 17 65 operates in order that the rocker arm may be moved. Each lever 17 is pivoted on a shaft 18 extending between the side bars 4 so that when power is applied to each lever 17 as at a point 19 between its ends, the rocker arm 70 will be caused to reciprocate. This pin 19 affords connection between each lever 17 and a yoked lever 20. This lever has no direct pivotal connection, but preferably bears by means of an extended finger 21 on each end 75 of the yoked lever against the shaft 14 carrying the rocker arm. The opposite end 22 of the yoked lever 20 carries the hooked end 23 of a link 24 which extends downwardly to a foot treadle, not shown, so that operation 80 of the lever-connected linkage may be caused to function the clamping bar 6.

In Fig. 1 the web-released position of the clamping bar 6 is shown, and in Fig. 2 the web-clamping position of the clamping bar is 85 shown. In order to cause the linkage to function so as to bring about these results, I provide fingers 25 and 26 extending from and attached to the respective shafts 14 and 18. These shafts are hooked at their lower ends 90 for attachment of the ends of a coil tension spring 27. The effect of this spring is to draw the fingers toward one another, thereby rocking the shafts 14 and 18, lifting levers 17 and rocker arms 13, and causing pins 11 to 95 bear downwardly upon yokes 12 which cause bar 6 normally to clamp the webs as shown in Fig. 2. Release of the webs is facilitated by downward movement of rod 24 through pressure upon its attached foot treadle, thereby 100

pulling downwardly upon the yoked lever 20 at its end 22, causing it to pivot upon the pins 19 and bringing its ends 21 against shaft 14 so that the pins 19 will be drawn downwardly 5 and therefore cause levers 17 to be drawn downwardly by pivoting on shaft 18 so that pins 16 thereof will operate in the slots of forked ends 15 of rocker arms 13. This causes rocker arms 13 to bring their pins 11 upwardly thereby lifting pins 10 and clamping bar 6 to the position shown in Fig. 1 so that the webs of paper are free to be released.

Cooperating with the mechanism I have just described is the paper cutter mechanism 15 which is located forwardly of the frame carrying the web-clamping and releasing mechanism which has just been described. This paper cutter mechanism is quite independent of the web-clamping and releasing mechanism, but, although cooperating therewith in 20 the functioning of the machine, is designed to be operated alternately with the operation of the clamping and releasing mechanism, being operated, however, by hand instead of 25 by foot as is the clamping and releasing mechanism through its treadle foot. This paper cutter mechanism is operated by a handle 28 mounted on a shaft 29 between plates 30 at the forward end of the machine frame. 30 Upon shaft 29 at each side of the frame and adjacent to the plates 30, is a gear segment 31 which meshes with the teeth of a rack 32 at each side of the frame and out of the path of travel of the paper webs as they are drawn 35 through the machine between the racks. Connecting the racks is a cutter bar or knife 33 extending across the webs and adapted to be brought downwardly upon them upon lifting movement of handle 28. The lower ends 40 of the racks 32 are rounded to provide in effect cam-shaped surfaces 34 adapted to cooperate with the face of a rocking bar 35 pivoted at a point 36 in each plate 30. This bar 35 carries a knife 37 which, when the 45 racks 32 are moved downwardly, will be forced to occupy a position such as shown in Fig. 2, against the back of knife 33 so that as the knife edges move over each other in shear-like fashion, the webs projecting beyond the 50 contacting faces of the knives will be cut off. A short spring 38 bears against the lower end of pivoted bar 35 to cause the bar normally to occupy the position shown in Fig. 1, but when the racks are moved downwardly, to be compressed as shown in Fig. 2.

This feature of a pivoting knife-bar is an important feature of the invention in that it performs two functions which, among others, are important. First, such a pivoting bar 60 permits of sufficient clearance away from the webs as to permit the fingers of the operator grasping the webs for pulling them forwardly off the aligning hooks 9. Second, the movement of the lower knife away from contact with the upper knife 33, also causes the

operation of the machine to be much safer by preventing the fingers of the operator being cut or scratched in pulling the webs forwardly or in even attempting to grasp the forward edges of the webs.

The lever 28 acts as a weight to keep the blades in their separated position.

Having thus described my invention, what I claim is:

1. Apparatus of the kind described comprising a blade, a second blade cooperating therewith, means including a manually operable pivoted lever for reciprocating the first-mentioned blade, and means for pivotally mounting said second blade, said last-mentioned means being adapted to cooperate with the first-mentioned means to bring said second blade into a functionally operative position each time the first mentioned blade is reciprocated.

2. Apparatus of the kind described comprising a pivoted lever, a pinion rotatable by said lever, a rack meshing with said pinion, a blade carried by said rack, a second blade cooperating with the first-mentioned blade, and means movable with the second blade and adapted to cooperate with said rack to bring said second blade into a functionally operative position.

3. Apparatus of the kind described comprising a pivoted lever, a pinion rotatable by said lever, a rack meshing with said pinion, a blade carried by said rack, a second blade pivotally mounted and cooperating with the first-mentioned blade, and means movable with the second blade and adapted to cooperate with said rack to bring said second blade into a functionally operative position.

4. Apparatus of the kind described comprising a movable blade, a second movable blade cooperating therewith, means for reciprocating the first-mentioned blade, the weight of said means normally holding the first-mentioned blade spaced from said second blade, and means constrained to move with said second blade and adapted to cooperate with the first-mentioned means for bringing said second blade into a functionally operative position each time the first mentioned blade is reciprocated.

5. Apparatus of the kind described comprising a movable blade, a second movable blade cooperating therewith, means including a lever for reciprocating the first-mentioned blade, the weight of said lever being utilized to hold the first-mentioned blade spaced from said second blade, and means for pivotally mounting said second blade, the last-mentioned means having a part secured thereto adapted to cooperate with the first-mentioned means for bringing said second blade into a functionally operative position each time the first-mentioned blade is reciprocated.

6. Apparatus of the kind described comprising a movable blade, a second movable blade cooperating therewith, means including a lever for reciprocating the first-mentioned 5 blade, the weight of said lever being utilized to hold the first-mentioned blade spaced from said second blade, means for pivotally mounting said second blade, the last-mentioned means having a part secured thereto 10 adapted to cooperate with the first mentioned means for bringing said second blade into a functionally operative position each time the first-mentioned blade is reciprocated, and yielding means for holding said blade in a 15 functionally inoperative position.

7. Apparatus of the kind described comprising a blade, a second blade cooperating therewith, means for reciprocating the first-mentioned blade, means for pivotally mounting 20 said second blade, and cam means constrained to move with the first mentioned blade for bringing the second blade into its functionally operative position each time the first-mentioned blade is reciprocated.

25 In testimony whereof I hereunto affix my signature.

PETER A. ASPENLEITER.
